K. SPENCER,

Priy Seat,

No 26866.

Patented Jan. 17, 1860.

UNITED STATES PATENT OFFICE.

KIRBY SPENCER, OF MINNEAPOLIS, MINNESOTA.

SEAT FOR WATER-CLOSETS.

Specification of Letters Patent No. 26,866, dated January 17, 1860.

To all whom it may concern:

Be it known that I, KIRBY SPENCER, of Minneapolis, in the county of Hennepin and State of Minnesota, have invented a new 5 and improved arrangement of means or devices for opening, holding open, and closing the covers of water closets or commodes for protecting upper surface of closing cover from being soiled by exhalations from said 10 water-closets and of preventing persons from standing on said seats while using the same; and I do hereby declare that the following is a full and exact description thereof, reference being had to the accompanying 15 drawings and to letters of reference marked thereon.

Figure 1, is a perspective view. Fig. 2, is a view of the under side of the top. Fig. 3, is a sectional view of the front. Fig. 4, 20 is a ground plan of the attached improvements on the under side of the top. Fig. 5, is a perspective view of a cleat. Fig. 6, is a perspective view of the sliding cover, with its attached bent projecting plate, and 25 straight projecting handle. Fig. 7, is a sectional view of the sliding cover, the top and front. Fig. 8, is an end view. Fig. 9, is a transverse section of the top and front.

The method of constructing my invention 30 is as follows: To a water closet seat, or commode, on its under side, is applied a cover B Fig. 2, made to move in one direction, by the pressure of the leg of a person against an attached handle, and in the opposite direction, by means of an attached 35 cord, pulley and weight; or other means.

A longitudinal groove A, A, Fig. 2, is cut in the front edge of the top, on its under side, in front of the aperture in the seat, of 40 the length of the space occupied by the attached devices to the top, and of a depth and width to receive a bent plate, G, G', Fig. 2, attached to the sliding cover B, Fig. 2. To this sliding cover, there is attached a 45 handle L, Fig. 2, which projects through a slot F, F, Fig. 1, cut in the upper edge of the front, of sufficient length and depth, to allow the handle to traverse it freely.

To the sliding cover, at its front edge a 50 bent plate, G, G', Fig. 2, is attached, of sufficient length to extend across the cover, and project beyond the slot, when the sliding cover is thrown to the back end of chamber. This plate is enough wider than the edge of 55 the cover, to reach to the bottom of the longitudinal groove A, A, Fig. 2, and then turn

an angle with the perpendicular portion of the plate, and wide enough to nearly cover the bottom of the groove. In this portion of the plate, is the point of attachment of 60 pulley cord; which attachment, is formed by a portion of the plate, being cut out, and a part of it bent over, forming a hook, as at C, Fig. 6. Also, there is cut a notch K, Fig. 2, in the perpendicular portion of the 65 plate, to permit the attachment of the projecting handle.

To the under side of the top, in front of the aperture, in the seat, is counter sunk, even with its surface, a plate A, Fig. 4, of 70 such a length, as to extend from opposite the position, occupied by place of cord attachment, when aperture is closed, to the middle of the chamber for sliding cover; and of a width, to project under the groove 75 A, A, Fig. 2, so as almost to touch the perpendicular part of the sliding plate; nearly leaving room for it to play.

A shallow rabbeting B, Fig. 7, and H, Fig. 8, is cut in the upper inner edge of the 80 front, of the length of the groove A, A, Fig. 2, in the top, and of sufficient depth to receive the perpendicular portion of the plate, and allow it to pass the side of the pulley, I, Fig. 2, and H, Fig. 8. There is also cut in 85 the front, at that portion which comes in contact with the chamber bottom, a gain I, Fig. 8, in the bottom of the rabbeting described for the front edge of the chamber bottom. 90

On the inside of the upper edge of the front, a gain E, E, E', Fig. 8, is cut, for the bearing of one end of pulley axle; also, a portion e, e, e, Fig. 8, of the front, is cut 95 away, for the weight to pulley to traverse. 95

In constructing seats of water closets, with the extended crooked shank, a hollow panel h, h, h, h, Fig. 1, is attached, by its sides J, J, Fig. 4, to the upper edge of the front, behind and below which panel, the bent shank 100 with its projecting handle traverses.

A cleat C, Fig. 2, is attached at the side of the seat aperture, of the length of the sliding cover. Against this cleat, the sliding cover closes. Another cleat D, Fig. 2, is attached 105 to the under side of the top, in the rear of the aperture. The form of this cleat, is seen in the perspective drawing of it, Fig. 5. The length of the rabbeting in this cleat, for sliding cover to traverse, is as much less than the width of the sliding cover, as to allow 110 the edge of the bottom of the chamber to lap

the edge of the closing cover, when the aperture is closed. The length of the rabbeting, forming end of the chamber, must be equal to the width thereof. A cleat F, Fig. 2, is attached to the top, at a point, where the side of the sliding cover stops, when the aperture in the seat is open.

The sliding cover B, Fig. 2, with its projecting handle and attached bent plate, may 10 be formed of one piece, and of any substance, cast, or otherwise.

The bottom E, Fig. 2, with its attached cleats, may be formed of one piece, and of any substance, cast, or otherwise.

15 In constructing and arranging the block and pulley, the top and front of the seat form the top and one side of the block; the other side being grooved from immediately below the pulley, and of such length that the 20 weight may traverse freely. This block must be so located, that the pulley will come immediately over the end of the groove A, A, Fig. 2, traversed by projecting portion of bent plate, and so that the cord may pass 25 from the groove over the pulley, in a plane perpendicular to the center of the bottom of the groove. And by inclosing the ends of the pulley block, a tight chamber will be formed for the pulley, cord, and weight to 30 work.

The operation of the invention is as fol-

lows, viz: The sliding cover is moved to one side of the aperture in the seat, and held open by the pressure, against the projecting handle, of the leg of the person sitting on 35 the seat; when the seat is unoccupied, the sliding cover closes the aperture in the seat, being moved and held there by means of the pulley and weight, or other means; all substantially as described herein.

40 I have thus described the general character of my invention and the manner of constructing and using the same.

What I claim as my invention and desire to secure by Letters Patent is—

45 The combination and arrangement of the slot F, F, with the projecting handles, with straight and bent shanks, E and G, the bent plate, G, G', the combined groove, A, A, formed by the rabbeting B, in the front, 50 and the groove, A, A, in the top, the plate A, the panel h, h, h, h, the chamber I, and the casement F, U, constructed in the manner above described and represented, and for 55 the purpose specified.

In testimony whereof I have hereunto signed my name before two subscribing witnesses this 1st day of December, A. D. 1859.

KIRBY SPENCER.
